US00D928526S

(12) **United States Design Patent** (10) Patent No.: **US D928,526 S**
(45) Date of Patent: **** Aug. 24, 2021**

(54) **CHAIR**

(71) Applicant: **GABRIELLA WHITE, LLC**, Pelham, AL (US)

(72) Inventor: **Kai-ning Huang**, Pelham, AL (US)

(73) Assignee: **Gabriella White, LLC**, Pelham, AL (US)

(**) Term: **15 Years**

(21) Appl. No.: **29/727,284**

(22) Filed: **Mar. 10, 2020**

(51) LOC (13) Cl. **06-01**

(52) U.S. Cl.

USPC **D6/380**
